(57) **CLAIM**

The ornamental design for a wafer holding member or the like, as shown and described.

DESCRIPTION

FIG. 1 is a front elevational view of a wafer holding member or the like, showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a top, front and right side perspective view thereof;

FIG. 8 is a bottom, front and left side perspective view thereof; and,

FIG. 9 is a cross-sectional view thereof taken along line 9—9 in FIG. 1.
